CLAIM

The ornamental design for retractor surgical instrument, as shown and described.

DESCRIPTION

FIG. 1 is an oblique, top-down perspective view drawing of the invention with open jaws.

FIG. 2 is an oblique, bottom-up perspective view drawing of the invention with closed jaws.

FIG. 3 is top-down view of the invention with closed jaws.

FIG. 4 is top-down view of the invention with open jaws.

FIG. 5 is drawing of the invention seen from one side;

FIG. 6 is drawing of the invention seen from the other side;

FIG. 7 is a front view of the invention; and,

FIG. 8 is a rear view of the invention.
